CLAIM

The ornamental design for a kiosk, as shown and described.

DESCRIPTION

FIG. 1 is a front-top perspective view of a kiosk showing my new design;

FIG. 2 is a front-bottom perspective view thereof;

FIG. 3 is a rear-top perspective view thereof;

FIG. 4 is a rear-bottom perspective view thereof;

FIG. 5 is a rear elevational view thereof;

FIG. 6 is a front elevational view thereof;

FIG. 7 is a left elevational view thereof;

FIG. 8 is a right elevational view thereof;

FIG. 9 is a top plan view thereof;

FIG. 10 is a bottom plan view thereof;

FIG. 11 is a left cross-sectional view taken along cutting line 11-11 in FIG. 9;

FIG. 12 is a front-top perspective cross-sectional view taken along cutting line 11-11 in FIG. 9;

FIG. 13 is a rear-top perspective cross-sectional view taken along cutting line 11-11 in FIG. 9;

FIG. 14 is a left cross-sectional view taken along cutting line 14-14 in FIG. 9;

FIG. 15 is a front-top perspective cross-sectional view taken along cutting line 14-14 in FIG. 9;

FIG. 16 is a rear-top perspective cross-sectional view taken along cutting line 14-14 in FIG. 9; and,

FIG. 17 is a supplemental front-top perspective view of the kiosk with a logo.

The broken lines shown are for illustrative purposes only and form not part of the claimed design.
